UNITED STATES PATENT OFFICE.

FRANK D. WARD, OF NEW YORK, N. Y.

SLACK-ADJUSTER FOR RAILWAY-BRAKES.

1,112,504.

Specification of Letters Patent.

Patented Oct. 6, 1914.

Application filed January 9, 1914. Serial No. 811,157.

To all whom it may concern:

Be it known that I, FRANK D. WARD, a citizen of the United States, residing in the borough of Manhattan of the city of New York, in the State of New York, have invented certain new and useful Improvements in Slack-Adjusters for Railway-Brakes, of which the following is a specification, reference being had to the accompanying drawings, forming a part hereof.

This invention relates generally to slack adjusters of the type shown in an application filed by the present applicant on July 28, 1913, Serial No. 781,489, in which is employed a rack bar movable longitudinally in one direction to take up the slack in the brake rigging after excess travel of the pull rod by reason of such slack. The present invention seeks to improve the devices of said prior application and is concerned particularly with the provision of means for locking the rack bar against accidental movement in either direction. The inertia of the rack bar and its associated parts under sudden impulses, such as are received when two or more cars are coupled together or when a car equipped with the slack adjuster devices is started or stopped, is considerable, and indeed may cause the bodily movement of the rack bar from its normal position of rest, thereby taking up prematurely the needed slack in the brake rigging. By the present invention the rack bar is held against movement in one direction under such external forces by the holding dog and in the other direction by means of an improved pawl which may not only serve to hold the rack bar against such accidental movement but in accordance with the illustrated embodiment constitutes the take-up pawl and as such performs its usual function.

The invention will be described more particularly with reference to the accompanying drawings, in which—

Figure 1 is a fragmentary view in side elevation of part of the wheels and truck of a railway car equipped with the improved slack adjuster. Fig. 2 is a view on an enlarged scale, in side elevation, of the improved adjuster, part of the casing being removed to show the operative parts of the adjuster and the brakes being applied so that the take-up rod is partially retracted from its position within its casing. Fig. 3 is a view taken on the plane indicated by the line

3—3 of Fig. 2 and looking in the direction of the arrows.

The construction and operation of so much of the brake system as is necessary for a clear understanding of the present improvements will be pointed out before the latter are described in detail, the present system, for the sake of convenience being identical with that illustrated and described in the co-pending application above referred to, although it will be understood as this description proceeds that the present invention is not to be limited in its application to a system of the precise form.

In Fig. 1 is illustrated, in a somewhat conventional manner, the application of the slack adjuster system to a car. The brake shoes *a*, *a* are shown as suspended by links *b*, *b* from the car truck (not illustrated) and controlled in their movement by a live lever *c* and a dead lever *d* respectively, these operating levers being interconnected adjacent their lower ends by the usual bottom rod *e*. The upper end of the dead lever *d*, which constitutes the adjustable fulcrum of the brake rigging, is connected through a suitable chain *d'* with a rack bar *d''* slidably disposed within a suitable casing *f* suspended from the car truck as through a clamp *g* and links *h*. The rack bar *d''*, which may be of substantially the same form as that illustrated in said co-pending application, has formed thereon a series of teeth *d''* with which co-operates a spring-pressed holding dog *i*, and a second series of teeth *d''* disposed at any desired and practicable angle with respect to the first named series of teeth. It will now appear that so long as the dog *i* is in engagement with the teeth *d''* of the rack bar *d''* movement thereof to the right, as viewed in Fig. 1, either by manipulation or accidentally, as through the influence of external shocks, cannot occur.

The inner side walls of the inclosing casing *f* are formed to receive a sliding take-up rod *k* operatively connected through a chain *k'* with the upper end of the live lever *c* and the usual pull rod *l*, the latter being connected to a suitable source of power. The inner end of the take-up rod *k* may be supported and guided in its movement by a pin *k''*, the ends of which are disposed within suitable longitudinal grooves *f'* formed in the opposite side walls of the supporting casing. Pivotal mounted on the pin *k''* within the casing is the improved pawl *m*

which may have in addition to its pivotal movement, a bodily movement with respect to the pin h^2 through the inclined slot m' within which the pin rests. The toe m^2 of 5 the pawl m coöperates with the teeth d^4 of the rack bar d^2 , the toe being provided with an integral stud m^3 , the end of which rests somewhat loosely in guide grooves or shoulders f^2 also formed in the inner side walls 10 of the supporting casing f . The inner ends of the grooves or shoulders f^2 are inclined, as at f^3 , as shown best in Fig. 2, so that when the take-up rod h is forced leftwardly (as viewed in this figure) to its extreme 15 position, the stud m^3 , following the inclination f^3 of the guide grooves f^2 , serves to retract the pawl m from its engagement with the teeth d^4 of the rack bar d^2 . This movement of the take-up rod h and the pawl m , 20 when the brakes are released, is brought about by a suitable spiral spring n disposed within the casing f and interposed operatively between one end wall of the casing and the pawl m so as to tend to force the 25 latter upwardly with respect to the pin h^2 and maintain said pin in the lower end of the slot m' , as indicated in full lines in Fig. 2. The inner end of the spring n preferably 30 abuts against a washer n' which, in turn, abuts against the rear face of the pawl m , this rear face being preferably curved so as to facilitate its movement along the washer n' in the manner to be described hereinafter.

The description thus far given applies in 35 all substantial respects to the brake system disclosed in the co-pending application referred to, save for the slot m' in the pawl m and it is believed that such description is sufficient to enable the application of the 40 present improvements to be understood. The body of the pawl m preferably has, in the present embodiment, its forward and upper face formed with a curved or cam surface m^4 , which engages an inclined or cam face 45 f^4 formed on the inner end wall of the casing f , when the pawl m is forced leftwardly (as viewed in Fig. 2) to its extreme position under the influence of the spring n . The cam face f^4 in its illustrated form or the 50 cam m^4 may be omitted entirely without departing from the scope of the invention, although it is necessary that there be provided a suitable abutting surface, such as a shoulder f^5 , to lock the pawl m in operative engagement with the rack bar as will later appear. At the lower part of the rear face of 55 the pawl m is formed a second toe or lug m^5 which, upon the abutting of the cam faces f^4 and m^4 in the manner referred to above, is moved downwardly into and is held in engagement with the beveled teeth d^4 of the 60 rack bar d^2 and engages the same effectively so as to hold the rack bar against accidental movement to the left (as viewed in Fig. 2), 65 as under the influence of external forces.

The operation of the improved devices may be summarized briefly as follows: When there is no excess slack in the rigging and the brakes are released, the pawl m is held at the extreme left end of the casing f , 70 as indicated in dotted lines in Fig. 2, the stud m^3 resting adjacent the ends of the shoulders f^2 and the pin h^2 , of course, remaining in the grooves f^2 . In reaching this extreme position the tension of the take-up spring n is sufficient to rock the pawl m bodily on its cam face m^4 along the cam face f^4 , so as to throw the body of the pawl m downwardly until the pin h^2 rests in the upper end of the slot m' . The form and size 80 of the parts are such that when the pawl m is in its extreme downward position the toe or lug m^5 engages effectively the beveled face of one of the teeth d^4 of the rack bar d^2 so as to prevent the accidental movement of 85 the rack bar to the left (as viewed in Fig. 2.) The locking engagement of the pawl m with the rack bar indeed becomes a positive one in that any tendency of the rack bar to move to the left (as viewed in Fig. 2) serves 90 merely to wedge the pawl m more securely between the shoulder f^5 and the teeth d^4 with which the lug m^5 engages, the spring n assisting this action. It will be evident 95 that movement of the rack bar in the opposite direction is prevented positively by the engagement of the dog i with one of the teeth d^3 of the rack bar d^2 . Upon application of the brakes, the pawl m is moved toward the right (as viewed in Fig. 2) and as 100 the cam face m^4 is moved from under the shoulder f^5 in its locked position it rides up the cam face f^4 , under the influence of the spring n in the manner above described, and disengages the lug m^5 from the teeth d^4 105 thereby permitting the rack bar d^2 to be moved to the left (as viewed in Fig. 2) in case there is slack to be taken up upon the subsequent release of the brakes.

The rack bar d^2 , as illustrated, may be 110 rotatable as in the copending application referred to, being provided with a handle a^5 to facilitate manual operation, the effect of rotating the rack bar being to move the teeth d^4 and d^3 out of engagement with the dog i 115 and lug m^5 respectively and permit the rack bar to be slid longitudinally to release completely the brake rigging and permit necessary adjustments or repairs to be made.

As suggested hereinbefore modifications 120 in the details of construction of the brake system and the arrangement of its elements may be made without departing from the spirit of the present invention, the improved devices being equally applicable and 125 serviceable in connection with other forms of brake rigging functioning in substantially the same manner.

I claim as my invention:

1. The combination of a car body, a truck, 130

- a brake system comprising a live lever and a dead lever and an automatic take-up device including supporting means mounted on the car body and comprising a rack bar 5 and a take-up rod both slidably mounted in said supporting means, a holding dog in engagement with the rack bar to hold the same against movement in one direction, a series of teeth on the rack bar, a pawl carried by 10 the take-up rod, a shoulder being formed on the supporting means and cooperating with the pawl to hold the same out of engagement with the teeth of the rack bar during normal travel of the pull rod and 15 permitting engagement of the pawl with the teeth of the rack bar upon excess travel of the pull rod and means to force the pawl into positive locking engagement with the teeth to prevent movement of the rack bar 20 in the opposite direction after the brakes have been released.
2. The combination of a car body, a truck, a brake system comprising a live lever and a dead lever and an automatic take-up device 25 including supporting means mounted on the car body and comprising a rack bar and a take-up rod, a pawl pivotally mounted on the take-up rod and connecting the same operatively with the rack bar, the supporting means and the pawl being provided with coöperating cam surfaces to force the pawl into locking engagement with the rack bar to hold the same against movement in 30 one direction when the brakes are released
- and a spring-pressed holding dog mounted on said supporting means and engaging the rack bar to prevent positively movement thereof in the opposite direction.
3. The combination of a car body, a truck, a brake system comprising a live lever and a dead lever, a casing supported on the car body, an automatic take-up device supported in said casing and including two rods operatively connected to the dead lever and to the pull rod respectively, a pawl supported pivotally within said casing on the inner end of the pull rod and operative upon excess travel of the pull rod to connect said two first named rods, guide shoulders formed on the inner side walls of the casing and co-operating with the toe of said pawl to determine its position, the body of said pawl being provided with a slot to receive the pivot pin of the pawl, a spring in operative engagement with the body of the pawl to hold the same normally out of engagement with the rack bar and coöperating cams formed on the inner wall of the casing and on the body of the pawl to force the latter into locking engagement with the rack bar after the brakes have been released.

This specification signed and witnessed this eighth day of January A. D. 1914.

FRANK D. WARD.
